(57) **CLAIM**

The ornamental design for a cell phone, as shown and described.

DESCRIPTION

FIG. 1 is a front view depicting our ornamental design when closed;

FIG. 2 is a rear view thereof;

FIG. 3 is a right side view thereof;

FIG. 4 is a left side view thereof;

FIG. 5 is a top plan view thereof;

FIG. 6 is a bottom plan view thereof;

FIG. 7 is a front view depicting our ornamental design when opened;

FIG. 8 is a rear view when opened;

FIG. 9 is a right side view when opened;

FIG. 10 is a left side view when opened;

FIG. 11 is a top plan view when opened; and,

FIG. 12 is a bottom plan view when opened.

The even broken line showings of portions of the cell phone throughout the views are for illustrative purposes only and form no part of the claimed design. The uneven, short-dash lines indicate the boundary of, but form no part of, the claimed design.
